UNITED STATES PATENT OFFICE

2,460,532

MOLD FOR CASTING WALL SLABS

Leslie-Ross Porter, Jr., Peabody, Mass.

Application October 12, 1945, Serial No. 621,987

2 Claims. (Cl. 25—121)

1

This invention relates to the art of casting slabs of concrete or other plastic material and the erection of these slabs from a horizontal plane in which they are cast to a vertical or intermediate plane.

Objects of the invention are to provide apparatus which permits the slab to be cast in horizontal position, which is simple and economical in construction, which permits the slab to be lifted in position quickly and easily after it has set, which does not keep the lifting means idle while the slabs are being formed nor while they are setting.

According to the present invention the apparatus comprises the combination of means having a horizontal surface upon which a slab may be cast, together with a frame having members for lifting the slab, the aforesaid surface having openings for the members, and strips fitting into the openings flush with the aforesaid surface for closing the openings, the strips being interposed between the frame and the slab and being loose so that they lift away from the aforesaid means when the slab is lifted. In a more specific aspect the frame comprises both longitudinal and horizontal members and the openings or spaces to receive the members are open at the ends so that the members may be inserted after the slab has been cast. In a still more specific aspect the apparatus comprises a plurality of forms spaced apart to provide the aforesaid spaces therebetween, the upper surfaces of the forms being disposed in the same horizontal plane. However in the broader aspect of the invention the surface upon which the slab is cast may comprise a floor having grooves therein to receive the frame members.

For the purpose of illustration a typical embodiment of the invention is illustrated in the accompanying drawings in which

Fig. 1 is a plan view with parts broken away;

Fig. 2 is a side elevation;

Fig. 3 is a longitudinal section on line 3—3 of Fig. 1;

Fig. 4 is a perspective view of the aforesaid frame with a part of the slab broken away; and

Fig. 5 is a perspective view of means for preventing the slab from falling off the frame when the frame is tilted to upright position.

The particular embodiment of the invention chosen for the purpose of illustration comprises a plurality of forms spaced apart to provide longitudinal spaces 1 and transverse spaces 2. These spaces are bridged with longitudinal strip 3 and transverse strip 4 whose upper surfaces are flush

with the upper surfaces of the form. Thus the forms and strips constitute means having a continuous upper surface upon which a slab of concrete or the like may be cast.

In the illustration the longitudinal and transverse spaces 1 and 2 divide the base into nine sections, including three short sections at each end and three long sections intermediate the two transverse spaces 2. Each of the nine forms 10 comprises a horizontal top wall 6 and uprights 7 for supporting the top walls, the uprights 7 extending beyond the edges of the top walls to support the longitudinal and transverse strips 3 and 4. The uprights 7 are supported on joists 8 which in turn are supported on beams 9. All of these parts may be secured together as by nailing. Bridging the longitudinal spaces 1 intermediate the upper and lower ends of the spaces are guides 11 and bridging the transverse spaces 2 at a somewhat higher level are guides 12; these guides being supported in any suitable way as by toe-nailing them in place along their edges. The guides 11 extend continuously throughout the length of the longitudinal spaces but the transverse guides 12 are interrupted throughout the widths of the longitudinal spaces (Fig. 2). In molding the slab 8 the concrete is confined around the edges by the usual screed 13 nailed to the upper surfaces of the forms.

30 The aforesaid frame comprises longitudinal members 16 and transverse members 17. The longitudinal members are interconnected at one end with a crosspiece 18 and braces 19 to form a rigid U-shaped member. Fast to the inner faces of the longitudinal member 16 are lugs 21 which project up to the upper edges of the transverse members 17 to keep the latter, which are not fastened to the longitudinal members, from slipping lengthwise of the longitudinal members 25 when the frame is tilted from horizontal to vertical position. The transverse members are preferably made in two parts which are interconnected by bolts extending through openings 22 in their overlapping portions (Fig. 2) to permit 40 them to be adjusted in length so that they do not project beyond the lateral edges of the slab. As shown in the drawings the ends of the spaces 1 and 2 are open so that the frame members may be inserted after the slab has set. In this 45 operation the U-shaped frame 16—19 is slid into place on the guides 11 with its open end foremost and the transverse members are slipped into place on the guides 12 from one side or the other. To facilitate insertion of the frame members the 50 distance between the longitudinal guides 11 and

the bottom of the longitudinal strip 3 is preferably somewhat greater than the maximum vertical dimension of the frame and the vertical distance between the upper surfaces of the longitudinal guide 11 and the transverse guide 12 is preferably somewhat greater than the vertical dimension of the longitudinal members 16.

To prevent the slab from slipping off the frame when the frame is tilted, the frame is preferably provided with feet 23 which, in the illustrated embodiment, comprise T-shaped pieces 23 sliding into channel guides 24 which are fast to the ends of the longitudinal members 16 and which may project somewhat above the upper surfaces of these members, the members 23 being detachably held in place by pins 26 (Fig. 3). On their upper ends the members 23 have flanges 27 to prevent the slab from slipping off the feet after the frame has been tilted to upright position.

To provide recesses in the slab for the feet 23, blocks 28 are placed against the inner face of the screed 13. After the slab has set the blocks are removed to admit the feet. The strips 3 should terminate in the vertical planes of the inner faces of the blocks 28 so as not to obstruct the feet. While the blocks 28 should not overlap the ends of the strips 3 they may overlap the adjacent forms enough to hold them up or they may be secured to the inner face of the screed. At the other end of the strips 3 the screed is provided with removable sections 29 to permit the strips and frame to be lifted with the slab without otherwise disturbing that end of the screed.

The closed end of the V-shaped frame may be provided with one or more movable hooks to overhang the edge of the slab to prevent the slab tipping off the frame when tilted to upright position. These hooks may be mounted on the frame either pivotally or slidably to permit them to be moved back and forth between operative and inoperative positions. The particular means shown in Figs. 4 and 5 comprises a hook slideable back and forth on one of the longitudinal frame members 16. The hook comprises a piece of angle-iron 31 fastened to a piece of channel-iron 32 which is mounted between two pieces 33 and 34, the parts 32, 33 and 34 having sliding engagement with the frame 16 on all four sides of the frame member.

In lifting the slab from the bed the frame, or at least the open end thereof, is preferably lifted

vertically before being tilted to upright position, so that the screed along the edge of the slab at the open end of the frame need not be removed. While the frame may be lifted in any suitable way it is preferably lifted by a jack under each of the two feet 24. After the open end of the frame has been thus lifted the other end of the frame is lifted by a crane or the like to tilt the slab into upright position. After it is secured in this position the frame is lowered to disengage the feet from the lower edge of the slab.

It should be understood that the present disclosure is for the purpose of illustration only and that this invention includes all modifications and equivalents which fall within the scope of the appended claims.

I claim:

1. In the art of casting wall slabs the combination of means having a horizontal floor upon which a slab may be cast, narrow elongate longitudinal and transverse sections of said floor being freely liftable away from said means, said means having spaces under said sections to receive longitudinal and transverse members, said spaces being open at the ends so that the members may be inserted into the spaces longitudinally and transversely respectively after the slab has been cast.
2. In the art of casting wall slabs the combination of means having a horizontal floor upon which a slab may be cast, narrow elongate longitudinal and transverse sections of said floor being freely liftable away from said means, said means having spaces under said sections to receive longitudinal and transverse members in superposition at different levels, said spaces being open at the ends so that the members may be inserted into the spaces longitudinally and transversely respectively after the slab has been cast.

40 LESLIE ROSS PORTER, JR.
